UNITED STATES PATENT OFFICE.

EDWARD SCHILDAUER, OF CHICAGO, ILLINOIS, ASSIGNOR TO EUGENE DIETZGEN COMPANY, A CORPORATION OF ILLINOIS.

APPARATUS FOR BLUE-PRINTING.

SPECIFICATION forming part of Letters Patent No. 687,272, dated November 26, 1901.

Application filed March 11, 1901. Serial No. 50,677. (No model.)

To all whom it may concern:

Be it known that I, EDWARD SCHILDAUER, a citizen of the United States, residing in the city of Chicago, county of Cook, and State of Illinois, have invented a new and useful Improvement in Apparatus for Blue-Printing, of which the following is a specification.

My invention relates to apparatus for reproducing drawings, tracings, and the like by the process commonly known as "blue-printing," in which sensitized paper is exposed to light in contact with the sheet or plate from which the reproduction is to be made.

It is well known that in the usual procedure the copy sheet or plate is placed between the sensitized sheet and a glass plate, the said sheets being pressed against the glass and subsequently exposed to rays of light entering through said glass. For the purpose of excluding light from behind and also for the purpose of effecting a more evenly distributed pressure of the sensitized sheet against the copy sheet or plate a pad of felt or other fabric is placed behind and forced against the said sensitized sheet, it being well understood that it is a great desideratum to maintain the said sheets in close contact with each other.

The objects of my invention are, first, to provide an apparatus having an air-tight frame from which the air may be quickly and easily exhausted, thereby permitting the weight of the outside atmosphere to act upon the diaphragm of the frame for the purpose of maintaining close contact of the sheets, and, second, to so construct the frame and diaphragm that artificial light—for example, from an arc-lamp—may be used to advantage both with regard to convenience and economy.

It is also my object to provide certain details more specifically set forth hereinafter.

I attain these objects by the mechanism shown in the accompanying drawings, in which—

Figure 1 is a perspective view of the complete apparatus. Fig. 2 is a plan view of the printing-frame. Fig. 3 is a detail view, in vertical section, showing the arrangement of the parts at the upper rim of the printing-frame. Fig. 4 is a plan view in detail of the parts as in Fig. 3. Fig. 5 is a plan view in

detail of a portion of the upper rim of the printing-frame, showing construction of the door-hinges. Fig. 6 is a detail view in elevation, showing the mechanism for locking the 55 swinging diaphragm-doors.

Similar characters refer to similar parts throughout the several views.

The printing-frame comprises the upper and lower rings *a* and *b*, respectively connected and supported by the uprights *c* and *d*. The said rings and uprights constitute frameworks wherein are mounted the glass plates *e e*, said plates being let into said rings and uprights in such a manner as to form air-tight joints therewith. Thus in the particular construction shown the main constituent part of the printing-frame consists of two half-cylinders of glass set in a preferably metallic framework. The said upright *c* at the 70 rear of the frame forms a point of attachment for the hinges *f f* of the diaphragm-doors *g g*, as shown in detail in Fig. 5. Said diaphragm-doors each consist of the uprights *h h* and *i i*, connected by the top members *j j* and bottom members *k k*, which together constitute frameworks similar in configuration and dimensions to the frameworks wherein the glass plates *e e* are mounted. The uprights *h* are secured to the hinges *f* above mentioned, so that said doors *g* may swing outwardly about the upright *c* as an axis. Extending across the area bounded by said door members *h*, *i*, *j*, and *k* are the diaphragms *m m*, which make air-tight connection therewith, preferably upon the inner surfaces thereof, and consist of sheets of rubber, rubber-covered canvas, or other fabric which is flexible and at the same time impervious to air. In order to insure air-tight connection 80 between the members *a* and *j* and *b* and *k*, respectively, when said doors *g* are closed and to insure such connection between the upright members *c* and *h* and *d* and *i*, respectively, there is provided a gasket or 85 washer *n*, which consists, preferably, of a strip of rubber or rubber-mixed fabric placed between the opposing surfaces and desirably secured to such of the above-mentioned members as are stationary.

A convenient form of lock for forcing the doors *g g* closely into contact with the sta-

tionary portions of the frame is indicated in Figs. 1, 2, and 6, the upright *d* having the shafts *o* supported thereon, so as to rotate about a vertical axis. Said shaft is provided 5 with eccentric portions adapted to rotate within collars *p*, formed upon the hasps *r*. Said hasps have at their free extremities heads *s*. The members *i* of the diaphragm-doors have slots *t*, adapted to receive the 10 shanks of said hasps *r*. The shafts *o* are rotated by means of a handle *u*, and the parts are so constructed that when the door *g* is closed and the shank of the hasp *r* placed within the slot *t* the rotation of said shaft *o* 15 will by means of its eccentric portion force said hasp against the upright *i*, thereby effecting a tight closure of said door *g*.

Suspended by means of the hooks *v* or in any other suitable manner is a pad *w*, consisting, preferably, of felt or carpet and occupying a position between the glass *e* and the diaphragm *m*, as shown in Fig. 3. The purpose of said pad is to distribute the pressure of said diaphragm in the manner above referred to.

From the construction of the printing-frame as described it is evident that when the diaphragm-doors are closed an air-tight chamber is formed between the diaphragm *m* 30 and glass *e*. When the air is exhausted or partially exhausted from said chamber, the weight of the outside atmosphere acting upon said diaphragm causes the latter to press toward the glass *e*. The air-duct *x*, formed 35 in the ring *a*, affords an outlet for the air from said chamber, as shown in detail in Fig. 3. Said duct is connected with the vacuum-tank *y* by means of the piping *z*, said piping being provided with valves 1. Said 40 tank is desirably provided with a gage 2 and is connected with the air-pump 3 by means of the hose or piping 4. The specific means for exhausting air from said tank *y* is immaterial; but for illustration I have shown said 45 pump 3 pivotally supported upon the bearings 5, the piston-rod 6 being connected to the crank 7 upon the shaft 8. Said shaft is mounted in the bearings 9 and is rotated by the gear 10, driven by the pinion 11. Said 50 pinion is driven by means of the motor 12. In the present instance the light for printing is supplied by the lamp 13, suspended from the revolving barrel 14, concentric with and controlled by the sheave 15. Said sheave is 55 mounted in the bracket 16, preferably secured to the ring *a* of the printing-frame. A motor 17, also on said bracket, is connected to said sheave 15 for rotating the same. The lamp 13 is so suspended as to hang centrally in the 60 printing-frame, and the operation of said motor causes the raising and lowering of said lamp.

In operation one or both of the doors *g* are thrown open and the sensitized paper, together 65 with the drawing or sheet to be reproduced, is placed between the pad *w* and the glass plate *e*. The door is then closed and brought

firmly into place against the main portion of the frame by means of the locking devices described, an air-tight chamber being thereby 70 formed between the glass *e* and the diaphragm *m*. By means of the pump 3 air has been previously removed from the vacuum-tank *y*, the valves 1 in the meantime having been closed. After the doors *g* have been firmly 75 closed the valves are opened, permitting the air confined within the frame to escape into the vacuum-tank *y*. As the vacuum is already formed in the tank *y*, the air quickly rushes out of the printing-frame, and the atmospheric 80 air pressing upon the outer surface of the diaphragm causes the sensitized paper and the tracing to be firmly pressed at all points against the glass plate *e*. Motor 17 is then set in motion to raise and lower the lamp 13 85 within the cylindric printing-frame until the time of exposure to the light of the lamp 13 has been sufficient. The valves 1 are then closed and the doors *g* are opened, thereby affording access to the contents of the frame 90 for removing the same.

It will be understood that the chief advantage in employing a vacuum-tank is that the air may be quickly exhausted from the printing-frame and also that a reasonably constant vacuum may be maintained without continuous use of the pump. On account of the joints and imperfect contact between the reciprocating parts of the pump there would be a leakage if the pump were directly connected to the printing-frame and a continuous action of the pump would be necessary during printing. In my apparatus the air may be exhausted from the tank and the connection between the tank and the pump subsequently shut off. Under these latter conditions by employing a tank of sufficient size a slight leakage in the printing-frame would have practically no effect upon the vacuum-gage pressure.

What I claim as new, and desire to secure by Letters Patent, is—

1. In a photographic-printing apparatus, the combination of a plurality of cylindrical plates of glass, frame-pieces bordering each 115 of said plates of glass and making air-tight connection therewith, said frame-pieces and glass plates forming an upright cylinder; door-frames hinged to said cylinder, an air-proof diaphragm extending across each of 120 said door-frames, means for making air-tight connection between said diaphragm and the cylinder-frame, a vacuum-tank, and connections between said tank and the space between said diaphragm and said glass plate 125 for exhausting the air from said space.

2. In a photographic-printing apparatus, the combination of a plurality of cylindrical plates of glass, frame-pieces bordering each 130 of said plates and making air-tight connection therewith, said frame-pieces and glass plates forming an upright cylinder; door-frames hinged to said cylinder, an air-proof diaphragm extending across each of said door-

frames, means for making air-tight connections between said diaphragm and the cylinder-frame, a vacuum-tank, a non-collapsible duct formed in one of said frame-pieces 5 whereby air may be exhausted from between said diaphragms and said glass plates after said doors are closed, and pipe connections between said tank and said duct.

3. In a photographic-printing apparatus, 10 the combination of a plurality of cylindrical plates of glass and frame-pieces bordering each of said plates thereby forming an upright cylinder; air-proof diaphragms, frames for said diaphragms, hinged to said cylinder 15 and forming diaphragm-doors; rubber gaskets adapted to come between the corresponding parts of the door-frames and cylinder-

frames for making air-tight contact between the parts; means for exhausting air from between said diaphragms and said glass plates; 20 shafts revolubly mounted on the stationary parts of the frame, said shafts having eccentric portions, hasps on said eccentric portions for engaging the door-frames, and means for rotating said shafts to thereby force 25 said door-frames closely onto said gaskets for making air-tight connections between said door-frames and the stationary portions of the frame.

EDWARD SCHILDAUER.
